(57) **CLAIM**

The ornamental design for a fishing reel, as shown and described.

DESCRIPTION

FIG. 1 is a first perspective view of a first embodiment of a fishing reel that includes a fishing reel portion in accordance with my new design;

FIG. 2 is a second perspective view of a fishing reel that includes a fishing reel portion in accordance with my new design;

FIG. 3 is a first side elevational view of the fishing reel illustrated in FIG. 1 that includes the fishing reel portion; FIG. 4 is a second side elevational view of the fishing reel illustrated in FIG. 1 that includes the fishing reel portion; FIG. 5 is a top plan view of the fishing reel illustrated in FIG. 1 that includes the fishing reel portion;

FIG. 6 is a bottom plan view of the fishing reel illustrated in FIG. 1 that includes the fishing reel portion;

FIG. 7 is a rear elevational view of the fishing reel illustrated in FIG. 1 that includes the fishing reel portion;

FIG. 8 is a front elevational view of the fishing reel illustrated in FIG. 1 that includes the fishing reel portion but in which the fishing reel portion is completely hidden from sight;

FIG. 9 is an enlarged perspective view, similar to FIG. 1, of the fishing reel portion illustrated in FIG. 1;

FIG. 10 is an enlarged perspective view, similar to FIG. 2, of the fishing reel portion illustrated in FIG. 1; and

FIG. 11 is an enlarged rear elevational view, similar to FIG. 7, of the fishing reel portion illustrated in FIG. 1; and,

FIG. 12 is an enlarged rear elevational view of a second embodiment of a fishing reel, which is identical to the fishing reel portion illustrated in FIGS. 1 to 11, except that a selected boundary of the fishing reel is shown in broken lines.

in the drawings, the broken line illustration of the environmental structure (the remaining structure of the fishing reel)

(Continued)

in the drawings is not part of the claimed design. In other words, the broken line portion of the fishing reel does not form part of the claimed design. Also, in the drawings, the dot-dash broken lines illustrate the boundary of the enlarged drawing views and form no part of the claimed design.
